(57) **CLAIM**

The ornamental design for a fitness tracker, as shown and described.

DESCRIPTION

FIG. 1 is a front, top perspective view of a fitness tracker according to a first embodiment of our new design.

FIG. 2 is a front, bottom perspective view thereof.

FIG. 3 is a rear, top perspective view thereof.

FIG. 4 is a rear, bottom perspective view thereof.

FIG. 5 is a top plan view thereof.

FIG. 6 is a bottom plan view thereof.

FIG. 7 is a right side elevational view thereof.

FIG. 8 is a left side elevational view thereof.

FIG. 9 is a front elevational view thereof.

FIG. 10 is a rear elevational view thereof.

FIG. 11 is a further perspective view thereof with a band attached to the fitness tracker.

FIG. 12 is a further perspective view thereof with a band attached to the fitness tracker.

FIG. 13 is a front, top perspective view of a fitness tracker according to a second embodiment of our new design.

FIG. 14 is a front, bottom perspective view thereof.

FIG. 15 is a rear, top perspective view thereof.

FIG. 16 is a rear, bottom perspective view thereof.

FIG. 17 is a top plan view thereof.

FIG. 18 is a bottom plan view thereof.

FIG. 19 is a right side elevational view thereof.

FIG. 20 is a left side elevational view thereof.

FIG. 21 is a front elevational view thereof.

FIG. 22 is a rear elevational view thereof.

FIG. 23 is a further perspective view thereof with a band connected to the fitness tracker; and,

FIG. 24 is a further perspective view thereof with a band connected to the fitness tracker.

The broken lines show portions of the fitness tracker and a band therefor that form no part of the claimed design.
